UNITED STATES PATENT OFFICE

113,921

DESIGN FOR A HAT

Elizabeth Schoen, New York, N. Y.

Application February 11, 1939, Serial No. 82,922

Term of patent 3½ years

To all whom it may concern:

Be it known that I, Elizabeth Schoen, a citizen of the United States, residing at New York, in the county and State of New York, have invented a new, original, and ornamental Design for a Hat, of which the following is a specification, reference being had to the accompanying drawing, forming part thereof, wherein—

Figure 1 is a front view;

Fig. 2 is a side view slightly in perspective from the rear; and

Fig. 3 is a top plan view of the hat showing my new design.

I claim:

The ornamental design for a hat, substantially as shown.

ELIZABETH SCHOEN.
